GAME BOARD

Charles P. Chalcroft, 815 25th Ave. W., Eugene, Oreg.

Filed Mar. 25, 1960, Ser. No. 59,865

Term of patent 14 years

(Cl. D34—5)

The figure is a top plan view of the game board embodying my new design, the board being flat and of conventional thickness.

The dominant features of my design reside in the portions shown in full lines.

I claim:

The ornamental design for a game board, substantially as shown and described.
